UNITED STATES PATENT OFFICE.

JOEL A. HAYES, OF SAN FRANCISCO, CALIFORNIA.

DYNAMO-ARMATURE.

SPECIFICATION forming part of Letters Patent No. 399,328, dated March 12, 1889.

Application filed May 2, 1888. Serial No. 272,608. (No model.).

To all whom it may concern:

Be it known that I, JOEL A. HAYES, a citizen of the United States, and a resident of San Francisco, in the county of San Francisco and State of California, have invented 5 certain new and useful Improvement in Dynamo-Electric Machines or Motors, of which the following is a specification.

My invention relates to the mechanical construction of ring-armatures for dynamo-electric machines or motors.

The armature involved in my invention is constructed in sections and the sections are built up of insulated laminated iron plates, 15 and is described in detail in the accompanying drawings.

Figure 1 is a side elevation of nearly one half of the armature, the other half being of the same construction. Fig. 2 is a sectional view of the whole armature, the section being 20 in a plane passing through the axis of the armature, and through the periphery of the armature midway between any two coils. Fig. 3 is a top view of one of the coils, showing also of 25 small portion of the armature on each side of the coil. Fig. 4 is a sectional view of one of the cores of the coils, the section being in a plane at right angles to the axis of the armature and passing through the center of the core; 30 and Fig. 5 is a top view of the core shown in Fig. 4. Fig. 6 is an end view of the plate *g*, showing the holes *i* for ventilation and holes *h* for the passage of the plates forming the 35 cores of the coils. Fig. 7 is a sectional view of a portion of the armature-ring at right angles to the axis of the ring, showing more clearly the internal construction of the ring.

The armature consists of the combination of a hub, *a*, spokes *b*, radiating from the said 40 hub, the said spokes containing holes adapted to receive screws *c* and *c'*, rivets or similar retaining devices, arc-curved iron plates *d*, separated by arc-curved sheets of insulating material, *e*, both containing holes through 45 which pass the said screws *c*, surrounded by insulating-tubes *f*, the outside plates of iron being thicker than the others for the sake of stiffness, the said plates and sheets being attached in sets to each of said spokes, and the 50 sets being separated by coils wound upon cores or spools, described particularly by reference to Figs. 4 and 5.

Each core consists of the combination of two brass or other non-magnetic plates, *g*, and strips or plates *h* of iron connecting the brass 55 plates, passing through the brass plates, and containing holes, which come opposite similar holes in the plates *d*, and through which pass the screws *c'*. An extension of each plate *h* lies between every two of the plates *d*. Holes 60 *i* are contained in the brass plates *g*, and air-spaces *j* are contained between some of the plates *h*, so that air may leak into the interior of the core, especially during the draft caused by the rapid rotation of the armature, 65 thereby reducing the heating effect of the electric currents to a minimum.

The *modus operandi* is as follows: The currents of electricity flow through the coils, while the magnetic currents are in the direction of the plates—*i. e.*, at right angles to the direction of the electric currents. The extensions of *h* are arc-curved, so as to fit in between the arc-curved plates *d*. By having the outer plate thicker than the plates toward 75 the center it becomes possible to make the latter as thin as the ordinary sheet-iron, thereby increasing the number of layers and reducing the Foucault currents. In any given case the thickness is such as to obtain the desired 80 rigidity.

In Fig. 6 screw-heads are shown between the slots. It is by these screws that the plates *g* are fastened to the plates upon which the coils are wound.

I claim as my invention—

1. In a dynamo-electric machine or motor, a ring-armature consisting of the combination of armature-coils wound upon rectilinear iron plates, and arc-shaped plates laminated 90 and connecting the first-named plates.

2. In a dynamo-electric machine or motor, a ring-armature consisting of the combination of separable laminated sections, and coils wound upon alternate sections.

3. In a dynamo-electric machine or motor, a ring-armature consisting of the combination of radial supports provided with holes, insulated arc-curved iron plates arranged in sets which are respectively located at each 100 sets of said supports, pairs of non-magnetic disks located between the said sets of iron-plates, separated rectilinear iron plates connecting the members of each pair and extending be-

tween the arc-curved plates, and bolts or similar retaining devices passing through the arc-curved iron plates and through the extensions of the iron plates which connect the 5 members of the pairs of non-magnetic plates and into the holes in said radial supports.

4. In a dynamo-electric machine or motor, a ring-armature consisting of the combination of coils provided with cores of laminated 10 insulated rectilinear iron plates, arc-curved extensions upon the plates and containing holes, laminated insulated arc-curved iron plates whose ends fit among the said extensions and whose ends contain holes, and bolts 15 or similar retaining devices passing through the arc-curved iron plates, and other bolts passing through said holes, and all the bolts being secured to radial supports around a suitable hub, the bolts being surrounded by insulating-tubes.

5. In a dynamo-electric machine or motor, a ring-armature consisting of the combination of alternate arc-curved and rectilinear insulated iron plates and arc-curved extensions upon the said rectilinear plates, fitting among the said arc-curved plates, the said combination being attached to a central hub, and the said rectilinear plates being provided 25 with coils of conducting-wire, such as copper.

30 6. In a dynamo-electric machine or motor, a ring-armature consisting of the combina-

tion of alternate arc-curved and rectilinear insulated iron plates, arc-shaped extensions upon some of the said rectilinear plates fitting among the ends of the said arc-curved plates, 35 one set of bolts, insulated, passing through the arc-curved plates, a second set of bolts passing through the ends of the arc-curved plates and through the said extensions, and a suitable central support receiving the ends of 40 all the screws.

7. In a dynamo-electric machine or motor, a ring-armature consisting of the combination of separable sections of laminated iron plates, and coils wound upon alternate sections, which are provided with polar extensions projecting among the plates of the immediately adjacent sections.

8. In a dynamo-electric machine or motor, an armature-coil whose core consists of a set 50 of separated iron plates connecting non-magnetic plates, and projecting through them to form polar extensions.

In testimony that I claim the foregoing as my invention I have signed my name, in presence of two witnesses, this 9th day of April, 55 1888.

JOEL A. HAYES.
